UNITED STATES PATENT OFFICE.

SAMUEL B. WHITEHEAD, OF SAN FRANCISCO, CALIFORNIA.

HAND OR WIRE VISE.

SPECIFICATION forming part of Letters Patent No. 269,903, dated January 2, 1883.

Application filed July 18, 1882. (No model.)

To all whom it may concern:

Be it known that I, SAMUEL B. WHITEHEAD, a citizen of the United States, residing at San Francisco, in the county of San Francisco and State of California, have invented a new and useful Improvement in Hand or Wire Vises, of which the following is a specification.

The object of my invention is to give increased holding and pressing facilities to hand or wire vises; and the invention consists in making a hand or wire vise with arms, link attachments, stationary shaft, and loose ferrule or band, as hereinafter specified.

In the accompanying drawings, Figure 1 is a longitudinal section of my improved vise. Fig. 2 is a side view thereof. Fig. 3 shows the inside of one of the clinching-jaws. Fig. 4 is a transverse section taken in the line *x x*, and Fig. 5 is a transverse section taken in the line *y y*.

A A are the arms, and *a a* the jaws thereof. *B* is the shaft, made stationary and threaded outside and hollow inside, and *b* a broken space therein to show the hollow. *C C* are the connecting-links between the arms and loose ferrule. *D* is the handle; *E*, a solid ferrule threaded inside on the upper end of the handle, and *e e* the shoulders of such ferrule; *F*, the loose ferrule or band around the solid ferrule of the handle, and *H* the connecting hinge or joint at the upper end of the shaft.

Similar letters refer to similar parts in all the drawings.

In using my invention I insert the wire or other material to be held between the jaws *a a* of the arms *A A*, and then turn the handle, and thus cause it to move up the threaded shaft *B*. The handle, moving up the shaft, shoves the connecting-links *C C* upward and

outward, and this spreads the lower ends and 40 closes the upper ends or jaws of the arms *A A*. This closing of the jaws produces a strong and equal pressure from each side, and thus forms a secure fastening or solid grip for the wire or other material to be held. The turning of the handle is reversed to open the jaws. The shaft, having a solid connection by means of the hinge or joint *H* at its upper end, always remains stationary, and the shaft, being hollow, so that the wire can pass into or through 50 it, admits of the holding of a wire of any desired length. The loose ferrule or band *F* around the solid ferrule admits of the handle being revolved, so as to move up and down the stationary shaft, as above mentioned. 55

The advantages of my invention are that its link motion greatly increases the holding and pressing power of a hand or wire vise, and, having no thumb-screw in the way at the upper end, it is more convenient than the ordinary 60 hand or wire vises now in common use. It is also capable of being used as a bench-vise when enlarged and properly connected.

Having thus described my invention, I claim as new and desire to secure by Letters Patent— 65

1. The combination, in a hand or wire vise, of a stationary shaft, arms, connecting-links, loose ferrule, and handle, substantially as described, and for the purpose set forth.

2. The combination, in a hand or wire vise, of 70 the stationary threaded shaft *B*, arms *A A*, connecting-links *C C*, loose ferrule *F*, threaded ferrule *E*, and handle *D*, substantially as described, and for the purpose set forth.

SAMUEL B. WHITEHEAD.
